UNITED STATES PATENT OFFICE

HENRY E. WEBER, OF CANTON, OHIO, ASSIGNOR TO THE WEBER DENTAL MANUFACTURING COMPANY, OF CANTON, OHIO, A CORPORATION OF OHIO

HEADREST

Application filed November 26, 1928. Serial No. 321,877.

The invention relates to head rests for dental chairs and the like, and includes common subject matter set forth in my prior application for patent for head rests, filed 5 June 25, 1927, Serial No. 201,435, of which the present application is a continuation in part.

For attaining maximum usefulness, a dental head rest should be adjustable 10 through a wide range of positions, so that children as well as adults, of all sizes, may use the same head rest.

On the other hand, for the proper making and fitting of false teeth, it is essential that 15 the head rest shall maintain vertical the upwardly and downwardly extending axis of the patient's head.

It is equally essential that after the rest pads of the head rest are adjusted for the 20 proper elevation of the patient's head with respect to the seat of the chair, that no movement of the rest pads may occur which shall change the elevation or lateral positions of the rest pads.

25 For such purposes, head rests including ball and socket joints, or permitting rotation of the rest pads about a vertical axis, are inadequate.

Accordingly the objects of the present 30 improvements include the provision of a head rest, adapted for use in the foregoing manner, and the parts of which are also arranged so that the patient's hair or the dentist's finger is not caught and pulled or pinched during adjustment of the head rest.

These and ancillary objects are attained 35 in the present improvements, a preferred embodiment of which is hereinafter set forth in detail, and is illustrated in the accompanying drawings forming part hereof, in which

Figure 1 is a fragmentary side elevation of a dental chair equipped with the improved head rest hereof, the head rest being 40 adjusted for use by a child;

Fig. 2, a view similar to Fig. 1, in which the parts of the head rest are shown in full lines in an extreme position of adjustment, and in dot and dash lines in a position of adjustment for use by an adult;

Fig. 3, a front elevation thereof as in the direction of the arrows 3-3, Fig. 2; and

Fig. 4, a rear elevation thereof, in which the rest pads are rotated to a different position than that illustrated in Fig. 3.

Similar numerals refer to similar parts throughout the several views.

A yoke 1 may be formed at the upper end of a vertically adjustable head rest supporting bracket 2 on the chair 3, and a horizontal shaft 4 is fixed therein as by the pins 5, and the shaft pivotally supports the clamping arm 6 of the improved head rest.

This clamping arm 6 is provided at its lower end with a bearing portion 7 journaled upon the shaft 4, and at its upper end with a similar bearing portion 8 within which is journaled a horizontal shaft 9.

As illustrated in Figs. 1 and 2, the clamping arm is split longitudinally as shown at 10, from the bearing portion 7 to the bearing portion 8, and at a point substantially halfway between these bearing portions the arm is cut through transversely at one side of the longitudinal central cut, as shown at 11. 75

As this arm is preferably formed from a malleable casting or the like, the two portions 12 thereof, separated by the transverse cut 11, will have a certain amount of resilience and will tend to assume their 80 natural or normal position. To prevent these portions from moving beyond this point, a screw 14 may be extended through a suitable bore at 15 near the free end of each portion 12 and be screwed into the solid 85 portion 16 of the arm.

A bolt 17 is screwed transversely through a threaded aperture in the center of the solid portion 16 of the arm and the bolt may be provided with a lock nut 18 at its 90 outer end. The bolt 17 has a head 19 located in a bore 20 formed in the free ends of the portions 12 and is provided with a flattened extremity 21 upon which is slidably mounted a collar 22 arranged to be engaged 95 by the cam 23 of a lever 24 which is pivotally mounted as shown at 25 upon the flattened extremity 21 of the bolt 17.

It will be seen that when the cam lever 24 is moved into the position shown in Fig. 1 100

the collar 22 will be forced inwardly against the free ends of the portions 12 of the arm, bending said portions inwardly toward the solid portion 16 and tightening the bearing 5 portions 7 and 8 of the arm around the horizontal shafts 4 and 9, respectively, clamping these shafts against movement in the bearings.

Supporting arms 26 and 26' are secured, 10 respectively, as by pins 27, upon opposite ends of the horizontal shaft 7 at the sides of the clamping arm 6.

The outer ends of the arm 26 and 26', terminate respectively, in bosses 28 and 28', 15 and the bosses 28 and 28' have formed therein, respectively, coaxial countersunk bores 29 and 29'.

The bosses 28 and 28' are located preferably at equal distances from the vertical 20 plane 30—30 perpendicular to the horizontal axis of the shaft 9, and passing through the midpoint thereof, and the common axis 31—31 of the boss bores 29 and 29', is preferably horizontal and parallel with the axis 25 of the horizontal shaft 9.

Accordingly, the shaft 9 being parallel with the shaft 4, the axis 31—31 will always be horizontal and perpendicular to the plane 30—30, regardless of the positions of the 30 clamping arm 6 and the supporting arms 26 and 26'.

A curved rest pad mounting bar 32, is enlarged at its opposite ends 33 and 33', respectively; and threaded sockets 34 and 34' 35 are formed in the ends 33 and 33', respectively, and receive the threaded inner ends of screws 35 and 35', respectively, which extend through and are journaled in the countersunk bores, respectively, of the bosses 28 and 28'.

Washers 36 and 36' are positioned, respectively, between the bosses 28 and 28' and the adjacent ends 33 and 33', respectively, of the curved rest pad mounting bar 32, in order that the bar may be easily rotated about the axis 31—31.

Rest pads 37 and 37' are secured at suitable angles on the bar 32 at equal distances from the plane 30—30, and for attaining the 50 objects of the present invention, the horizontal axis of rotation 31—31 of the bar 32 and attached rest pads 37 and 37', passes through the centers 38 and 38', respectively, of the rest surfaces 39 and 39', respectively, 55 of the rest pads 37 and 37'.

As best illustrated in Figs. 3 and 4, the rest pad mounting bar supporting arms 26 and 26' are curved outwardly in such manner as to permit the bar 32 and attached rest pads to make a complete rotation about 60 their axis 31—31, thus permitting the rest pads to be properly positioned with respect to the patient's head regardless of whether the various head rest parts are in the position 65 illustrated in Fig. 1 for supporting the

head of a child patient, or are in any other position.

If the bar 32 and rest pads 37 and 37' were not freely rotatable about their axis, the 70 position illustrated in Fig. 1 could not be attained.

Locating the centers 38 and 38' of the rest surfaces of the rest pads in the axis of rotation 31—31 of the rest pads, and stationarily mounting the rest pads on the bar 75 32, insures that after any adjustment of the head rest for a particular patient, regardless of the number of times the patient may remove his head from the head rest, his head will always resume substantially the 80 same elevation and position.

If the centers of the pad rest surfaces did not lie in the axis of rotation thereof, such a maintenance of the elevation and position 85 of the patient's head could not be attained.

The shafts 7 and 9 being horizontal and parallel with each other as aforesaid, and parallel with the axis of rotation 31—31 of the head rest pads, there is no possibility of 90 movement of the head rest pads about a vertical axis, when the dentist is taking impressions or fitting false teeth, and thus with the patient's back normally resting against the back of the chair, his head is positioned 95 so that his face looks directly forward, and the proper operations may be performed.

The arms 26 and 26' are laterally spaced from each other, and are spaced from the bar 32 and rest pads 37 and 37', so that the patient's hair and the dentist's fingers will 100 not be caught between the arms and the bar or rest pads during adjustment of the same.

I claim:

1. A head rest including supporting arms, a rest pad mounting member rotatably mounted on a horizontal axis on the arms rotatable through an arc of 360°, and spaced 105 rest pads stationarily mounted on the member, the axis of rotation of the member passing through the centers of the rest surfaces 110 of the pads.

2. A head rest including a bearing member, a horizontal shaft rotatably mounted in the bearing member, supporting arms secured upon the shaft and rotatable therewith, a rest pad mounting member rotatably mounted on a horizontal axis on the arms rotatable through an arc of 360°, the axis of rotation of the mounting member being parallel with the axis of the shaft, and spaced 115 rest pads stationarily mounted on the mounting member, the axis of rotation of the mounting member passing through the centers of the rest surfaces of the pads.

3. A head rest including a supporting bracket, a horizontal shaft secured in the bracket, a clamping arm, one end of the arm being rotatably mounted on the shaft, another shaft parallel with the first shaft and rotatably mounted at the other end of 120 125 130

the clamping arm, supporting arms secured upon the second shaft and rotatable therewith, a rest pad mounting member rotatably mounted on a horizontal axis on the arms, rotatable through an arc of 360°, the axis of rotation of the member being parallel with the axis of both shafts, and spaced rest pads stationarily mounted on the member, the axis of rotation of the member passing through the centers of the rest surfaces of the pads.

4. A head rest including a bearing member, a horizontal shaft rotatably mounted in the bearing member, supporting arms secured upon the shaft and rotatable therewith, a rest pad mounting member rotatably mounted on a horizontal axis on the arms and rotatable through an arc of 360°, and spaced rest pads stationarily mounted on the mounting member, the axis of rotation of the mounting member being parallel with the axis of the shaft and passing through the centers of the rest surfaces of the pads.

5. A head rest including a supporting bracket, a horizontal shaft secured in the bracket, a clamping arm, one end of the arm being rotatably mounted on the shaft, another shaft parallel with the first shaft and rotatably mounted at the other end of the clamping arm, supporting arms secured upon the second shaft and rotatable therewith, a rest pad mounting member rotatably mounted on a horizontal axis on the arms, and spaced rest pads stationarily mounted on the mounting member, the axis of the rotation of the mounting member being parallel with the axes of both shafts and passing through the centers of the rest surfaces of the pads.

40 In testimony that I claim the above, I have hereunto subscribed my name.

HENRY E. WEBER.
